UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A SPOON, FORK, OR SIMILAR ARTICLE.

40,549.

Specification for Design.

Patented Mar. 1, 1910.

Application filed December 29, 1909. Serial No. 535,539. Term of patent 7 years.

To all whom it may concern:

Be it known that I, HENRIK HILLBOM, a citizen of the United States, residing at Wallingford, in the county of New Haven and State of Connecticut, have invented a new, original, and ornamental Design for a Spoon, Fork, or Similar Article; and I do hereby declare the accompanying drawing to be a full, clear, and exact illustration of the same, and which said drawing constitutes part of this specification and represents a face view of a spoon, fork, or similar article embodying my design.

Claim.

The ornamental design for a spoon, fork or similar article as shown.

HENRIK HILLBOM.
